(57) **CLAIM**

The ornamental design for a confection container, as shown and described.

DESCRIPTION

A portion of the disclosure of this design patent document contains material to which a claim of copyright protection is made. The copyright owner has no objection to the facsimile reproduction of the patent document or the patent disclosure as it appears in the United States Patent and Trademark Office file or records, but reserves all other copyrights. FIG. 1 is a perspective view of a confection container design, in accordance with the present invention.

FIG. 2 is a side view of a confection container design, in accordance with the present invention.

FIG. 3 is a top view of a confection container design, in accordance with the present invention.

FIG. 4 is an opposing side view, taken at an angle of 90° relative to that of FIG. 2 of a confection container design, in accordance with the present invention; and,

FIG. 5 is a bottom view of a confection container design, in accordance with the present invention.
